UNITED STATES PATENT OFFICE.

LOUIS HARRIS, OF BIRMINGHAM, ALABAMA.

DESIGN FOR A MAIL BOX.

Application filed June 6, 1928. Serial No. 27,010. Term of patent 14 years.

To all whom it may concern:

Be it known that I, LOUIS HARRIS, a citizen of the United States, residing at Birmingham, in the county of Jefferson and State of Alabama, have invented a new, original, and ornamental Design for Mail Box, of which the following is a specification, reference being had to the accompanying drawings, forming a part thereof.

Fig. 1 is a front view of the mail box; and Fig. 2 is a side view thereof.

I claim:

The ornamental design for a mail box substantially as shown.

In testimony whereof I, LOUIS HARRIS, affix my signature.

LOUIS HARRIS.
